UNITED STATES PATENT OFFICE.

OSCAR KATZENBERGER, OF CHICAGO, ILLINOIS.

ENVELOP.

1,158,229.

Specification of Letters Patent. Patented Oct. 26, 1915.

Application filed April 27, 1915. Serial No. 24,215.

To all whom it may concern:

Be it known that I, OSCAR KATZENBERGER, a citizen of the United States, and a resident of Chicago, in the county of Cook and State of Illinois, have invented a new and Improved Envelop, of which the following is a full, clear, and exact description.

This invention relates to envelops and particularly to an improved envelop designed to be used for second class mail matter, and has for an object the provision of an improved simple structure which will positively hold the matter in the envelop against accidental movement therefrom while allowing at all times an examination by postal authorities or other authorized persons.

A further object of the invention is to provide an improved form of envelop in which a loose flap is utilized for holding mail matter in an envelop, the same being associated with what may be termed locking tabs in order to prevent, positively, mail matter from moving out of the envelop.

In the accompanying drawings:—Figure 1 is a plan view of an envelop embodying the invention, the same being shown in an unfolded condition; Fig. 2 is a side view of the envelop in position for receiving mail matter; Fig. 3 is a view of the envelop sealed and the retaining or inspection flap in an unfolded position; Fig. 4 is a sectional view through Fig. 3 on line 4—4, the same being on an enlarged scale.

Referring to the accompanying drawings by numerals, 1 indicates the body or face of the envelop while 2 and 3 indicate the end flaps, flap 3 carrying a strip or edge of adhesive 4 so as to secure the flaps 2 and 3 together when folded, as shown in Fig. 2. A side flap 5 is also provided with adhesive 6 so that when the envelop is folded to the position shown in Fig. 2 the mail matter may be inserted in the usual manner and flap 5 sealed in the usual manner. During the manufacture of the envelop the ends 2 and 3 are folded together so that the adhesive 4 will connect these two members, and the locking tabs 7 and 8 are folded so as to project beneath the flaps 2 and 3. A layer of adhesive is arranged on each of these tabs so that the tabs may be secured to the end flaps 3 and 4, as shown more particu-

larly in Fig. 4. Between the tabs 7 and 8 is arranged an inspection flap 9 loosely folded into the envelop beneath the ends 2 and 3. After the contents has been placed in the envelop, flap 5 is sealed, as shown in Fig. 3, but flap 9 is loosely positioned in the envelop and may be withdrawn, as shown in Fig. 3, in order that the inspectors may inspect the contents of the envelop when it is desired to remove the contents without tearing the envelop. The locking members 7 and 8 normally prevent the removal of the contents even when the flap 9 is unfolded, so that a person using the envelop may be assured that the contents will not accidentally be lost out. These locking tabs are intended to prevent accidental losing of the contents but not to prevent in any sense of the word a proper inspection or even removal of the contents by an authorized person. In arranging the locking tabs and inspection flap a space is provided therebetween which may be comparatively small or may be comparatively large. Preferably, however, the space 10 between the inspection flap 9 and the tabs 7 and 8 is only sufficient to allow a free removal and a free insertion of the inspection flap at any time.

By the construction and arrangement just described it will be observed that an envelop is presented which may be used by the person using the same as an ordinary envelop and be assured that the contents will remain in the envelop, while the envelop will pass through the mail as second class mail matter.

What I claim is:—

In an envelop of the character described, a body, a pair of end flaps extending from said body adapted to be folded over on the body, adhesive on one of said end flaps for connecting the last mentioned end flap with the other end flap, a side flap having adhesive arranged thereon so that the same may be secured to said end flaps when closed, a locking tab adjacent each end of said body and extending therefrom, said locking tabs being arranged on the opposite side of the body to said side flap, a layer of adhesive arranged on each of said locking tabs on the face contacting with said end flaps whereby the locking tabs may be secured to said end flaps and provide a sup-

port for the contents of the envelop in order to prevent an accidental removal thereof, and an inspection flap arranged between said locking tabs, said inspection flap being 5 spaced from said locking tabs in order to permit of an easy inspection and removal when inspecting the contents of the envelop.

In testimony whereof I have signed my name to this specification in the presence of two subscribing witnesses.

OSCAR KATZENBERGER.
